UNITED STATES PATENT OFFICE

99,806

DESIGN FOR A SADIROD OR SIMILAR ARTICLE

Russell I. Huffman, Dover, Ohio, assignor to The Dover Manufacturing Co., Dover, Ohio, a corporation of Ohio

Application March 5, 1936, Serial No. 61,482

Term of patent 7 years

To all whom it may concern:

Be it known that I, Russell I. Huffman, a citizen of the United States and a resident of Dover, in the county of Tuscarawas and State of Ohio, have invented a certain new, original, and ornamental Design for a Sadiron or Similar Article, of which the following is a specification, reference being had to the accompanying drawing, forming part thereof.

Figure 1 is a perspective view of a sadiron or similar article showing my new design.

and

Figure 5 is a rear elevational view thereof.
The dominant feature of my design resides in the portions shown in full lines.

I claim:

The ornamental design for a sadiron or similar article as shown and described.

RUSSELL I. HUFFMAN.
